J. H. WALKER, OF WORCESTER, MASSACHUSETTS.

Letters Patent No. 61,489, dated January 22, 1867

IMPROVED MACHINE FOR CUTTING SOLES.

The Schedule referred to in these Letters Patent and making part of the same.

KNOW ALL MEN BY THESE PRESENTS:

That I, J. H. WALKER, of the city and county of Worcester, and Commonwealth of Massachusetts, have invented certain new and useful improvements in Machines for Cutting Soles for Boots and Shoes from whole sides of leather; and I do hereby declare that the following is a full, clear, and exact description of the same, reference being had to the accompanying drawings, forming a part of this specification, in which—

Figure 1 represents a perspective view of my improved machine.

Figure 2 represents a central vertical section, the line of section being from front to back.

Figure 3 represents a top or plan view of one of the dies used to cut soles for boots and shoes; and

Figure 4 represents a side view of the die or cutter shown in fig. 3.

The principal object of my present improvement is to facilitate the cutting of soles for boots and shoes from whole sides of leather, in accordance with the patent granted to me on the 22d day of August, A. D. 1865.

In the drawings, A represents the floor or platform, upon which the legs B of the machine, and the supports C of the table or platform D, rest. E is the lower part of the frame of the machine, the front lower section or part F of which is removable, while the upper front part E' is connected to the front box part G of the upper part H of the frame of the machine by a neck piece H'. The upper and lower parts E H are connected at the rear by a strong upright piece, I. In suitable bearings, a b, upon the part H rests and turns the main shaft J, from the head of which projects the eccentric or crank-pin e, which receives the upper end of the connecting-rod or link d, the lower end of which is hinged at e to the division piece f, which unites the side pieces g g, which extend up from the top of platen K, and serve as guides to retain said platen in proper position. The side pieces g g are fitted to slide with a close fit in the guide-box G, which connects with the neck piece H' of the main frame. Platen K for convenience is not made solid, but with an outer rim, h, combined with central or cross-ribs, i. Between the parts F and E' are fitted four gears, two on each side. These gears have screw-threads cut in them to fit four screw-bolts or rods, which pass through the gears. The four screw-bolts or rods pass up through pieces F and E, and are fastened securely to the bottom of the bed-piece or cutting-block L. The screw-bolts and gears on one side have left-hand screw-threads, so that when the screw-shaft or spindle M, which fits into all four gears—two on each side—is turned, the bed-piece or cutting-block is elevated or lowered in a horizontal position. The gears being fitted into slots when they are revolved by the screw-spindle M, all the screw-bolts are elevated or depressed, together with the cutting-block L, so that the latter can be accurately adjusted in respect to the platen, whereby the leather can be cut by the die without the edge of the latter being forced into the face of the block or head-piece.

In lieu of the device above described for adjusting the bed, an inclined plane may be fitted between the bed and frame E, so that when said inclined plane is moved by a screw, or otherwise, in one direction, the bed will be elevated, and lowered when it is moved in the other direction. The upper part N of the bed or cutting-block is removable, so that the face of this part of the block can be planed off when roughened by much use. The block is cut so that the grain of the wood runs up and down. Upon the rear of shaft J is placed a balance-wheel, J', to which is fastened the driving-pulley O, both of which run loose upon the end of shaft J. A clutch, P, is placed upon the end of shaft J, the arms n n of which pass through guides connected with pulley O and wheel J'; a cap, o, on the end of shaft J prevents the clutch from slipping off the shaft. Clutch P is operated by the bent lever Q, fulcrumed at p, the long arm S extending under the frame E, and attached to the piece F by a spiral spring, x, as fully shown in the drawings. The action of the spring x keeps the clutch and its arms n n back, so that shaft J and platen K are not operated only when the front end of the long arm S of the lever Q is depressed so as to throw clutch P forward, as shown in red lines, fig. 2, in which case the arms n n are forced forward so far that they engage with the lugs or ears on the hub z of shaft J. The screw spindle M may be made with a thread cut only a few times around at the points where the thread engages the gears; the balance of the spindle may be left blank, and may be smaller for convenience of manufacture.

The operation is as follows: The operator takes the side of sole leather and spreads it upon table D, the part where he desires to commence cutting being placed under the platen K. The cutting-block or bed L having been adjusted, he places the die T upon the leather under the platen, and then, with his foot, depresses the

long arm S of lever Q, thereby throwing clutch P into operation, when motion is imparted to shaft J, and the platen K is forced down upon die T, and a sole is cut from the whole side of leather. As soon as the cut is made the operator removes his foot from lever Q, and spring x causes the clutch to move back, and shaft J stops by the time the platen is elevated, as shown in fig. 1. The operator now turns his die and moves the leather, if necessary, and the operation is repeated until the whole side of leather is cut up, according to the mode secured to me by Letters Patent granted on the 22d day of August, 1865. By the use of the open and independent die T, the operator can place it very quickly in the desired position, while he can as quickly remove the die, and, by a sudden blow, knock out the cut soles. This machine has been put to a practical test with very important results.

Having described my machine for cutting soles for boots and shoes, what I claim as new and of my invention, and desire to secure by Letters Patent, is—

1. The combination and arrangement of the broad table D for supporting the side of leather, with the adjustable bed or cutting-block L, and the reciprocating platen K, substantially as and for the purposes set forth.
2. The combination and arrangement, with the table D, bed L, platen K, and shaft J, of the peculiarly constructed frame, composed of the parts marked E H H' and G, substantially as described.
